UNITED STATES PATENT OFFICE

AUGUST J. HARTFIELD, OF HUNTINGTON PARK, CALIFORNIA, ASSIGNOR TO PACIFIC GAS RADIATOR COMPANY, OF HUNTINGTON PARK, CALIFORNIA

ADJUSTABLE THERMOSTAT FOR RADIATORS

Application filed May 26, 1931. Serial No. 540,061.

This invention relates to a heat-regulating device applicable to various types of heaters.

An object of the invention is to provide a device of this kind which can be more cheaply and conveniently attached to heaters now on the market, and one which will not disfigure or encumber the heater to which it is attached.

Another object of the invention is to simplify the thermostatically operated and pressure controlled elements of the device and to render them more positive and dependable in their operation.

Still another object of the invention is to provide an improved arrangement of cooperating thermostats which will under all conditions insure a safe operation of the heater.

Yet another object of the invention is to provide an improved connection between a fuel valve and the means for thermostatically actuating such valve.

Other objects, advantages and features of the invention may hereinafter appear.

Referring to the accompanying drawings which illustrate what is at present deemed to be a preferred embodiment of the invention,

Fig. 1 is an end elevation of the lower portion of a radiator showing the device applied thereto.

Fig. 2 is a section on line 2—2 of Fig. 1.

Fig. 3 is a section on line 3—3 of Fig. 2.

Fig. 4 is a side elevation of a radiator showing the device connected therewith.

Referring in detail to the drawings, and describing first the thermostatic device which is attached to the casing 10 of the radiator, said device comprises a bi-metallic thermostatic arm 11 which is laterally deflectable under the influence of heat. The upper end 40 of said arm is secured to the wall of the casing 10 by any suitable means as by the screw 12. Above said arm 11 a bracket 14 projects from the casing and is used to pivotally support a bell crank lever having a horizontally extending arm 15 and a downwardly extending arm 16, the latter arm having tapped therethrough an adjusting screw 17, the inner end of which is operatively related to the free end portion of the thermostatic arm 11.

50 The bracket 14 whereon the bell crank lever

just described is mounted, consists of a screw threaded stem 14a, a bifurcated head 14b and a lock nut 14c screwing on to said stem. The bell crank lever is pivotally secured to the bifurcated head 14b after the bracket 14 has been screwed into a screw hole provided therefor in the wall of the casing 10. The lock nut 14c serves to securely maintain the bracket 14 in the adjusted position. By this arrangement the operative connection between the thermostatic arm 11 and the valve 25 may be accurately regulated.

To the lower portion of the casing 10 is secured externally thereof the mixing chamber fixture 20, the otherwise open end of which is more or less obstructed by an adjustable cover 21 through which is fed the fuel pipe 22, these parts, separately considered forming no part of the present invention.

Fuel is fed to the pipe 22 past the fuel valve 25, said valve being provided with a stem 26 which is slidably contained within the fitting 27, said fitting being screwed into place as shown. Said valve stem 26 operates through a stuffing box 30, a wire stem 31 being tapped into the end of said valve stem. The stem 26 of the valve is provided at its outer end with a head 26a and this head is in an operative relation to the arm 15 of the aforementioned bell crank lever, said arm 15 having a bifurcated end portion which passes astride the stem 31. When the temperature of the radiator rises above a predetermined amount the thermostat operates the bell crank lever and causes its arm 15 to press against the head 26a of the valve stem 26 thereby shutting off further supply of fuel to the burner B. When the temperature decreases the bifurcated arm 15 recedes from the head 26a of the valve stem and allows the valve 25 to reopen.

Owing to the fact that the end portion of the wire stem 31 is at all times loosely contained within the socket which is provided in the end portion of the valve stem 26, said valve stem aids in safely maintaining said wire in its slidable operative position in alignment with said stem. Hence a very simple and dependable construction, which

is also easy to assemble, is provided for the purpose set forth.

Before the fuel reaches the valve 25 it is fed through an opening or passage 42 which is controlled by the double diaphragm 36 within the diaphragm casing 37, said casing 37 preferably being provided with a peripheral flange 38 whereby it is secured to the main casing of the radiator. After passing through the opening 42 the fuel is delivered by a channel 39 to the intake side of the valve 25 already mentioned. The passage 42 is controlled by the steam pressure, while the valve 25, as already explained, is controlled by the external dry heat produced by radiation.

Normally when the heater is in regular operation the steam operated double diaphragm 36 is spaced away from the main central supply opening 42, thus permitting the gas to freely enter the intermediate chamber 40 from the supply chamber 41 through the port 42. From the intermediate chamber 40 the fuel flows through the peripheral outlet 39 past the valve 25 to the burner B. When, however, the steam pressure rises sufficiently to close said central inlet opening, the only gas admitted enters through the small by-pass opening 45 into the intermediate chamber and thence out said peripheral opening to maintain the operation of the burner B, which would otherwise be completely extinguished. The double diaphragm 36 and parts immediately associated therewith are not, separately considered, a part of the present invention and are therefore not described in full detail.

In addition to the thermostatic control which includes the bi-metallic arm 11, another thermostatic control is provided, the latter control being associated with the pilot burner 46 and being arranged to operate the wire 31, the greater part of which is contained within a tube 46b. Said pilot burner is supplied with fuel by tube 46x. This thermostatic control is provided with a bi-metallic arm 50 constructed for lateral deflection like the arm 11 already described. Said arm 50 is, however, preferably placed within the radiator and at one end secured to the inner wall of the radiator by means of a screw 51, the free end of said arm 50 being in an operative relation to the end of the wire 31 which is tapped through the wall of the radiator as indicated in Fig. 4. The thermostatic arm 50 is placed so close to the pilot burner 46 that if the burner accidentally becomes extinguished the arm 50 will operate the wire 31 and thereby close the valve 25.

The operative connection between the wire 31 and valve 25 is best shown in Fig. 2 where it will be seen that said wire is led through a bushing 55 which has externally threaded end portions, a cap 56 being screwed upon the

outer end portion of said bushing. Said cap 56 has an aperture therethrough into which the adjacent end of the tube 46 is tightly fitted, means thus being provided to form a clamp tight fit. The wire 31 has a sliding fit within a socket provided therefor in the head 26a and outer end of the stem 26. This arrangement permits the bell crank arm 15 of the other thermostatic device to close the valve 25 without affecting the position of the wire 31 or the operation of the thermostatic arm 50.

I claim:

1. In a device of the kind described, the combination, with a valve to admit fuel, said valve having an operating stem with a relatively deep socket or bore in the end thereof, of two thermostatic devices each adapted to close said valve independently of the other and without interference with the other thermostat, one of said devices comprising a wire or stem having its end portion slidably and loosely fitted within said socket and during all operative positions retained therein and adapted to abut endwise against the bottom thereof, and the other thermostatic device comprising an arm with a bifurcated end portion which straddles said wire and which is adapted to impinge upon the end of said valve stem to close the valve.

2. In a device of the kind described, the combination with a fuel valve and dual thermostatic means for actuating said valve; of a stem forming a part of said valve and projecting outwardly therefrom, said stem having a relatively deep longitudinally extending socket in its outer end, and an operating rod projecting loosely into the socket of said stem, said operating rod being connected with one of the thermostatic controls and the other thermostatic control having an operating relation to said valve stem independently of said rod.

In testimony whereof I hereunto affix my signature.

AUGUST J. HARTFIELD.
